UNITED STATES PATENT OFFICE.

CLARE H. DRAPER, OF HOPEDALE, MASSACHUSETTS, ASSIGNOR, BY MESNE ASSIGNMENTS, TO DRAPER CORPORATION, OF HOPEDALE, MASSACHUSETTS, A CORPORATION OF MAINE.

WEFT-REPLENISHING LOOM.

Application filed November 21, 1925. Serial No. 70,462.

The present invention relates to an improvement in weft replenishing looms.

Heretofore the transerrer of a weft replenishing loom has comprised a hammer which engaged the butt of the bobbin to be transferred to the shuttle to replenish the weft therein, such transferred hammer having a tip engaging portion to engage the tip of the bobbin so as to secure the certain insertion of the bobbin in the shuttle. The tip engaging portion of the transerrer has been found, however, sometimes to cut the yarn extending from the bobbin outwardly to the yarn end holder, and this, of course, is for that reason objectionable. It has been proposed to provide a weft replenishing mechanism with a transerrer having a hammer adapted to engage the yarn in order to avoid cutting of the yarn at the tip. Such hammers, however, are not well adapted for use with pieces, that is, with bobbins not provided with a full supply of yarn.

According to the present invention the transerrer is provided with the usual hammer, with a yarn engaging portion and with a portion which, when the yarn is not sufficient to enable the yarn engaging portion to control the position of the bobbin, will engage the tip of the bobbin in such exceptional circumstances, and thereby secure the correct presentation of the bobbin to the shuttle. The invention consists in the weft replenishing loom hereinafter described and particularly defined in the claims.

In the accompanying drawings illustrating the preferred form of the invention, Fig. 1 is a transverse section through the hopper, showing the transerrer of a weft replenishing loom in position to transfer a bobbin from the hopper to the shuttle; Fig. 2 is a longitudinal section of the lower portion of the hopper, showing the relative positions of the bobbin and hammer at the time the hammer is about to insert a bobbin in the shuttle; Fig. 3 is a transverse section taken on the line 3-3, Fig. 2; and Fig. 4 is a transverse section taken on the line 4-4, Fig. 2.

The illustrated embodiment of the invention is described as follows: The hopper plate 1, the butt end disk 2, and the small end disk 3 of the weft replenishing mechanism of the loom are, or may be, of the usual form. The weft hammer 4 is pivoted at 5 in

the usual manner, and carries the butt end hammer 6, which is adapted to engage the butts 7 of the bobbins 8. The butt end hammer 6 is provided with a boss 9, which receives the rod 10, secured therein by means of the set screw 11, which carries a yarn engaging portion 12 and the bobbin tip engaging portion 13. The yarn engaging portion 12 comprises a segment of a cylinder carried by the post 14, which has formed upon it the boss 15, which is provided with a hole to receive the rod 10. A set screw 16 secures the boss upon the rod at the desired position. The curvature of the yarn engaging portion is made to correspond to that of the surface of the bobbin so that when it strikes the bobbin it will not cut it or injure it.

Supported from the right-hand end of the yarn engaging portion 12 (in a left-hand loom such as that shown in the drawings) there is the tip engaging portion 13 which, under ordinary circumstances, does not touch or engage the tip 18 of the bobbin. It is adapted, however, in exceptional circumstances, as, for example, where the bobbin is provided with only a portion of its load, to engage the tip of the bobbin and thereby secure the correct presentation of the bobbin to the shuttle.

The present invention eliminates the usual and regular engagement of the tip engaging portion of the hammer with the bobbin, and thereby reduces the losses due to the cutting of the yarn extending from the bobbin to the yarn end holder. In ordinary circumstances the yarn engaging portion of the hammer by engagement with the yarn in conjunction with the butt end engaging portion, effectively controls the movement of the bobbin from the hopper into the shuttle. But when, owing to some irregularity of operation which might be due to the fact that the bobbin was only partially filled, the shuttle would tend to tip, then the small end engaging portion of the transerrer strikes the tip of the bobbin and forces the bobbin directly into the shuttle.

Having thus described the invention, what is claimed is:

1. A weft replenishing loom having, in combination, a hopper, and a transerrer having a butt end engaging portion, an intermediate yarn engaging portion separate

- from the butt-engaging portion and provided with a tip engaging portion.
2. A weft replenishing loom having, in combination, a hopper, and a transerrer comprising a butt end engaging portion, a longitudinally extended, concave, yarn engaging portion, and a tip engaging portion normally located with relation to the yarn engaging portion in such position as not to engage the tip of the bobbin, but adapted to engage the tip when the bobbin is not provided with a full supply of yarn.
3. A weft replenishing loom having, in combination, a hopper, and a transerrer comprising a longitudinally extended butt end hammer, a longitudinally extended yarn engaging member, and a bobbin tip engaging member held from engagement with the tip by a full supply of yarn on the bobbin.
4. A weft replenishing loom having, in combination, a hopper, a transerrer having a butt end engaging portion, a tip engaging portion, and a long intermediate yarn mass engaging portion mounted in spaced relation to the butt end engaging portion and adapted to engage a large area of the yarn during bobbin transfer.
5. A weft replenishing loom having, in combination, a hopper, a transerrer, having a butt end engaging portion, an intermediate yarn engaging portion and a tip engaging portion, and means for supporting said yarn engaging portion and tip engaging portion for adjustment relative to the butt end engaging portion.

In testimony whereof I have signed my name to this specification.

CLARE H. DRAPER.
